STEREOSCOPIC VIEWER

Kenneth E. Golden, Portland, Oreg., assignor to Sawyer's Inc., Progress, Oreg., a corporation of Oregon

Filed Dec. 7, 1959, Ser. No. 58,580

Term of patent 14 years

(Cl. D61—1)

Fig. 1 is a front elevational view of a stereoscopic viewer embodying my new design;

Fig. 2 is a side elevational view thereof;

Fig. 3 is a bottom plan view thereof;

Fig. 4 is a top plan view thereof;

Fig. 5 is a rear elevational view thereof; and

Fig. 6 is a side elevational view of the side opposite the view in Fig. 2.

A portion of the device is translucent, as indicated by diagonal shading.

I claim:

The ornamental design for a stereoscopic viewer, as shown and described.
